LAMP

Florentino E. Zara, Maasin, Leyte, P. I.

Application November 5, 1934, Serial No. 751,616

4 Claims. (Cl. 67—38)

The invention relates to a lamp and more especially to a gravity feed oil lamp designed for the burning of cocoanut oil as a fuel.

The primary object of the invention is the provision of a lamp of this character, wherein the wick is raised and lowered in a novel manner and also the oil as fuel is delivered to the said wick by gravity and the feed of the oil is regulated to increase or decrease the flame when the lamp is lighted.

Another object of the invention is the provision of a lamp of this character, wherein the gravity action thereof is such as to assure the feeding of cocoanut oil in its original form and exclusively used as a fuel, there being continuous heat applied to the tank for the oil content so that the said oil cannot coagulate at low temperatures and a perfect combustion is assured.

A further object of the invention is the provision of a lamp of this character, wherein the construction thereof is novel in its entirety and the wick employed can be readily cleaned when lighted and also can be raised and lowered to vary the flame in the burning of the lamp.

A still further object of the invention is the provision of a lamp of this character which is comparatively simple in construction, thoroughly reliable and efficient in its operation, neat in appearance, readily and easily controlled or operated, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a side elevation of a lamp constructed in accordance with the invention.

Figure 2 is a vertical longitudinal sectional view thereof.

Figure 3 is an enlarged sectional view on the line 3—3 of Figure 2 looking in the direction of the arrows.

Figure 4 is an enlarged sectional view on the line 4—4 of Figure 2 looking in the direction of the arrows.

Figure 5 is an exploded perspective view of the flame spreader.

Figure 6 is a fragmentary perspective view of a turning stem.

Figure 7 is an exploded perspective view of the wick engaging rings.

Figure 8 is a perspective view partly broken away of the wick raiser.

Figure 9 is a perspective view of the chimney holder.

Figure 10 is a perspective view of the wick chamber.

Similar reference characters indicate corresponding parts throughout the several views in 10 the drawings.

Referring to the drawings in detail, the lamp comprises a lower oil reservoir 10 which is the base of the lamp, having rising therefrom the tubes 11 and 12, respectively, the latter tube being extended into the reservoir 10, while the tube 11 is closed off, at 13, from communication with said reservoir. These tubes 11 and 12, at their upper portions, are bent into close relation to each other, as at 14, and through the medium of separable couplings 15 have connection with a feed tank 16 which, in its top, has threaded therein a removable plug 17 which permits the filling of the tank 16 with oil, the tube 11 being adapted to function as a feeder 15 for oil and having arranged therein a hand operable valve 18 for shutting off the oil feed or the regulation of the same through the tube 11. The tube 12 communicates with a pump cylinder 19 built into the tank 16, it having communication with the latter through the perforations 20 in said cylinder and the piston 21 of the pump is manually operated within the pump cylinder 19, as usual. The purpose of the pump 30 is to lift oil from the reservoir 10 through the tube 12 into the tank 16, there being provided a return check valve 22 in said tube 12 to prevent the return flow of the oil in the tank 16 to the reservoir 10, as will be obvious.

The top of the reservoir 10 has the central 40 upstanding columnar portion 23 in which is arranged the combined wick and fuel font 24 which, through the union 25, has communication with the feed tube 11, so that oil from the tank 16 can be delivered to the font 24, and 45 detachably fitting this font is a burner head 26 providing a wick barrel 27 for a wick 28. The wick is fitted concentrically about a wick carrying ring 29, it having spaced oil channels 30 exteriorly therein, these being vertically disposed, while provided at the interior of the ring 29 are the threads 31 for engagement with a companion threaded head 32 on the head of a wick raiser 33 which is of tubular form and rotatably fitted in a cylinder 34 extended centrally 50 55

through the reservoir 10 and rising centrally of the portion 23 thereof.

Embracing the wick 28 exteriorly thereof and concentrically of the ring 29 is a two-part circular clamp 35 which is slidable in the barrel 27 and arranged in its parts at opposite sides are diametrically opposed guide ribs 36, vertically disposed in the barrel 27, the parts of the clamp 35 being formed with spurs or teeth 37 which bite into the wick 28, and the fitting of these parts with the ribs 36 prevents rotation of the wick 28 on the raising and lowering thereof by the wick raiser 33. The head of the wick raiser 33 is telescoped over a center column 38 of the font 24, through which extends the cylinder 34 having the wick raiser 33 therein, this column 38 at its upper open end being formed with apertures 39 to allow unspent fuel from the wick to drop back into the reservoir 10, as the column 38 is spaced concentrically from the said cylinder 34.

The wick raiser 33, at its lower end, extends exteriorly of the cylinder 34 and is formed with a knurled circular knob 40 which permits the manual turning of the said wick raiser 33, so that the ring 29 in its threaded engagement with the threaded head 32 of the raiser 33 can be moved to shift the wick 28 for raising and lowering thereof, as should be obvious.

The burner head 26 is provided with a chimney holder 41 for a glass chimney 42 having its upper contracted end 43 confronting a walled center opening 44 in the tank 16. This opening 44 functions as a heat passage and is covered by a perforated cap or crown 45 having centrally thereof a hanger ring 46, its stem 47 being passed through the cap or crown 45 and supporting a heat deflector disk 48 centered with respect to the opening 44 in the tank 16 so as to deflect the heat from the chimney 42 within the opening 44 in a lateral direction for the heating of the oil as contained within the tank 16 to assure free fluidity thereof, particularly during low temperatures.

The ring 46 permits the lamp to be hung from a suitable support when the same is in use.

Depending from the bottom of the tank 16 are the hangers 49 for a shade holder 50 having detachably fitted therein the shade 51 preferably made from glass and having heat resisting quality, this being also true with respect to the chimney 42. The shade holder 50 has fitting with the tubes 11 and 12. The hangers are provided with separable couplings 52, so that when it is desired to remove the shade 51 and the holder 50, the couplings 15 and 52, respectively, are separated, thus detaching the tank 16 and permitting the freeing of the said holder 50 and shade 51, as should be apparent.

Adjustably fitted in the upper end of the wick raiser 33 is the perforated cup 53 of a flame spreader 54, which may afford the proper spreading condition to the flame. This cup carries an internal cross bar 55 having a central eye 56 for a purpose presently described. On the underside of the flame spreader 54 is a knife edge wick cleaner 57, it being made secure to said spreader and provided with a central threaded eye for accommodating the upper threaded end of a turning stem or rod 58, the same being passed centrally through the raiser 33. The lower end of the stem or rod 58 is extended exteriorly of the raiser 33 and has a terminal hand knob 60 at its exterior end. The

stem or rod 58 also is passed through a spring barrel 61 centrally arranged within the wick raiser 33 and having therein the lifter 62 engaged with the stem or rod 58 for yieldably supporting it and holding the wick cleaner 57 normally above the flame end of the wick 28. Upon pulling the knob 60 the stem or rod 58 will be lowered to bring the cleaner 57 into position for the cleaning of the lighting end of the wick 28 and this is accomplished by the turning of the said cleaner 57 when in its lowered position. The cup 53 is retained on the stem or rod 58 as it is coupled therewith in the manner as shown and thus is retained therewith when the spreader 54 is removed.

The tube 12, through the separable union 64, has connection with the font 24, but this tube 12 is non-communicative with the font while the feed tube 11 does communicate therewith through the union 25.

The burner head 26 has the apertures 65 so that any excess oil accumulated by the wick 28 can return through the burner head 26 to the reservoir 10 through these perforations 65, as should be obvious.

The plug 17 has formed therein an air vent 66 to assure a gravity feed of oil from the tank 16 to the font 24, whence the oil therefrom is consumed by the flame from the wick 28 on the lighting of the lamp and the heat from this flame is conducted through the chimney 42 to the opening 44 in the tank 16, where the heat is utilized in part for the heating of the oil within the tank 16 to prevent the same coagulating, especially at low temperatures, and thus assuring perfect fluidity to the oil, it being cocoanut oil, as the lamp is constructed especially for this kind of oil for fuel.

The bottom of the reservoir 10 has a removable plug 67 for the purpose of drainage of 40 such reservoir when occasion requires.

The lower end of the tube 12 extended into the reservoir 10 has fitted therewith a suitable strainer 68 for oil content in said reservoir.

The burner head 26 has the reduced threaded portion 69 which is detachably threaded in the threaded neck 70 formed in the font 24 and this burner head 26 is readily separable therefrom.

The deflector disk 48 is suspended from the cap of crown 45 and is directly in the heat path 50 from the chimney 42.

The reservoir 10 in its side wall has provided therein a transparent window 71 having a graduated scale 72, so that a person can determine the quantity of fuel as may be contained within this reservoir and also when the same has been completely filled. In other words, the level of the fuel can be readily ascertained by the scale 72 as provided on the window 71.

At the juncture of the tube 11 and the tank 60 16 is arranged a strainer 73, this being placed within the coupling 15 and held seated at the joint between the said tube and tank, as will be seen in Figure 2 of the drawings.

A mantle holder 74 is provided at the burner 65 head 26 and the same is attached by hooks 75 which engage through suitable slots provided in the flange 76 outturned from the wick barrel 21. In mounting the mantle holder 74, the plate constituting the flame spreader 54 is removed, 70 leaving the cup 53 in place. The mantle holder 74 with its mantle 77 can be slipped over and attached to the burner head.

The burner head 26 carries a perforated laterally spread apron 78 for the purpose of giving 75

draft or supplying air to the lamp for the combustion of fuel to assure a perfect flame.

What is claimed is:

1. A lamp of the character described comprising an oil reservoir, a gravity feed oil tank, an oil font between the reservoir and tank, an oil feed tube leading from the tank to said font, a burner head on said font, a chimney holder on the head, a chimney fitted in said holder, a wick barrel formed in the burner head, a wick fitting said barrel, a wick raiser operating through said reservoir and manually controlled below the same, and means for delivering oil from the reservoir to the said tank.
- 15 2. A lamp of the character described comprising an oil reservoir, a gravity feed oil tank, an oil font between the reservoir and tank, an oil feed tube leading from the tank to said font, a burner head on said font, a chimney holder on the head, a chimney fitted in said holder, a wick barrel formed in the burner head, a wick fitting 20 said barrel, a wick raiser operating through said reservoir and manually controlled below the same, means for delivering oil from the reservoir to the said tank, the said tank having an opening aligned with the chimney, a perforated cap 25 overhanging the opening above the chimney, and a heat deflector depending from said cap.

3. A lamp of the character described compris-

ing an oil reservoir, a gravity feed oil tank, an oil font between the reservoir and tank, an oil feed tube leading from the tank to said font, a burner head on said font, a chimney holder on the head, a chimney fitted in said holder, a wick barrel formed in the burner head, a wick fitting said barrel, a wick raiser operating through said reservoir and manually controlled below the same, means for delivering oil from the reservoir to the said tank, the said tank having an opening aligned with the chimney, a perforated cap 10 overhanging the opening above the chimney, and a heat deflector depending from said cap.

4. A lamp of the character described comprising an oil reservoir, a gravity feed oil tank, an oil font between the reservoir and tank, an oil feed tube leading from the tank to said font, a burner head on said font, a chimney holder on the head, a chimney fitted in said holder, a wick barrel formed in the burner head, a wick fitting 15 said barrel, a wick raiser operating through said reservoir and manually controlled below the same, means for delivering oil from the reservoir to the said tank, the said tank having an opening aligned with the chimney, a perforated cap 20 overhanging the opening above the chimney, a 25 heat deflector depending from said cap, and a control valve arranged in said feed tube.

FLORENTINO E. ZARA.
